DOOR LATCH

Claud H. Saxton, Elmira, N. Y.

Application February 18, 1937, Serial No. 126,466

5 Claims. (Cl. 292—71)

This invention relates to a latch for doors and while it is designed primarily for use in connection with the doors of automobiles, it is to be understood that it can also be employed in connection with other types of doors, if found convenient.

An object of the invention is to provide the latch with a bolt which does not slide as ordinarily but is mounted to slide and swing relative to the latch housing and the keeper so that when the bolt is not fastened against swinging movement, the door can readily be moved into or out of closed position without requiring the use of handles such as commonly employed.

15 A further object is to provide simple and efficient means for fastening the bolt against movement relative to its housing.

With the foregoing and other objects in view which appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred forms of the invention have been shown.

In said drawings
30 Figure 1 is a side elevation of portions of two doors of an automobile, the same being equipped with latches which constitute the present invention, a portion of one of the doors being shown in section.

35 Figure 2 is a central vertical longitudinal section through the housing of the latch in one door.

Figure 3 is a section on line 3—3, Figure 2.

Figure 4 is a section on line 4—4, Figure 2.

40 Figure 5 is a section on line 5—5, Figure 2.

Figure 6 is a view similar to Figure 2 but showing the relative positions of the parts when the latch is released and retracted by the opening or closing of the door.

45 Figure 7 is a section on line 7—7, Figure 6.

Figure 8 is an enlarged section on line 8—8, Figure 1.

Figure 9 is a horizontal section through a portion of the latch showing the position of the bolt 50 while the door is being closed, the head of the bolt being pressed backwardly by contact with its keeper.

Figure 10 is a view similar to Figure 2 showing a slightly modified form of latch.

55 Figure 11 is a section on line 11—11, Figure 10.

Figure 12 is a section on line 12—12, Figure 10.

Figure 13 is an enlarged transverse section through a portion of the door equipped with the modified form of lock, the operating levers of 5 the latch and the shafts from which they are extended being shown.

Figure 14 is a perspective view of the head of the latch bolt.

Referring to the figures by characters of reference A designates a door of an automobile or the like, the same being of the usual construction with the exception that no handles are mounted on either the inner side or outer side thereof. Formed in the bottom wall of the window opening at opposite sides of the glass B are sockets C each of which is sufficiently large to receive one or more fingers of the user when it is desired to release the latch and open or close the door. Each of these sockets is located above the housing 1 of the latch which is concealed within the door at the usual location.

In the structure illustrated the latch housing comprises a metal plate bent to provide side walls 2 and an end wall or face plate 3, the latter being formed with an opening 4 in which the head of the latch bolt is adapted to work. This end wall or face plate 3 is adapted to lie flush or substantially flush with that edge of the door remote from the hinges and be supported close 20 to the keeper 5 of the latch when the door is closed.

As the housing of the latch is bent substantially into U-shape it can extend partly around the path of the window glass B as shown for example in Figures 7 and 8 so as not to interfere with the raising and lowering of the glass.

Guide ears 6 are struck inwardly from one of the side walls 2 of the latch housing or casing and slidably between them is a latch bolt 7 40 formed of an elongated strip of metal bent to produce a yoke having parallel arms. This bolt is straddled by a cross strip 8 slidably mounted on a pin 9 projecting from the adjacent side 2 of the casing and interposed between the cross strip 45 8 and the head 9' of the pin is a coiled spring 10 which constantly thrusts against the cross strip, thereby to press the bolt 7 yieldingly against the adjacent side wall 2 and maintain it between the 50 guide ears 6.

The head of the bolt is of peculiar design and has been illustrated in detail in Figure 14. This head 11 has a flat side 12 which merges into a rounded end surface 13 terminating at the outer end of the opposite flat side 14 of the head. This 55

flat side 14 extends backwardly to a laterally extending enlargement 15. Recesses 16 are provided in the top and bottom of the latch head at the inner end thereof and are adapted to receive the free end of the arms of bolt 7, these arms being joined to the head by a pivot 17. The parts are so proportioned and assembled that when in normal positions, the flat side 12 of the head and the corresponding side of the bolt 7 will rest snugly against the adjacent wall 2 of the latch casing as shown, for example, in Figure 4, these parts being held yieldingly in these positions by the pressure of spring 10 against the cross strip 8 which, in turn, thrusts against the bolt 7.

A spiral spring 18 is secured to one of the side walls 2 of the casing and has a free end which exerts a constant thrust against the inner end of the bolt 7 so that said bolt is held normally in forwardly extended position with the head 11 projecting through opening 4 and the enlargement 15 thrusting against the face plate 3 of the casing so as to constitute means for limiting the movement of the bolt in one direction. These positions of the parts are clearly shown in Figure 5 wherein the head of the bolt is shown in engagement with its keeper, as when the door is closed.

For the purpose of preventing swinging movement of the bolt 7 and the head 11, there is provided a detent 19 in the form of a short lever pivotally mounted at 20 on the inner side of the face plate 3 and normally supported by a stud 21 so that its end will bear against the adjacent side of the stop or enlargement 15. A lifting rod 22 connects detent 19 to an equalizing lever 23 pivotally mounted on the face plate 3 and provided at its ends with slots 24. Extending into the respective slots are the rounded ends of operating levers 25 and 26 which are pivotally supported on the respective side walls 2 and guided within straps 27 or the like. Those ends of the levers remote from slots 24 are engaged by push rods 28 mounted in guides 29 and extending into the respective sockets C where they are equipped with heads or push bars 30 adapted to receive thrust from one or more fingers of the user. If desired these heads can be made of such size as to constitute closures for the sockets 50 so as to keep out foreign substances.

A coiled spring 31 can be connected to the lever 25 for exerting a constant downward pull thereon with the result that the detent 19 is maintained normally in the position shown in Figure 3, thereby preventing lateral swinging motion of bolt 7 and head 11. It does not, however, interfere with the back and forth sliding motion of the bolt.

Actuation of the equalizing lever 23 by the depression of either of the rods 28 can be prevented by a pivoted stop 32 located above the lever and adapted to hang downwardly into position thereagainst. By means of a rod 33 extending inwardly from the door and attached at one end to this stop, the stop can be swung into or out of restraining position. In Figure 3 the stop has been shown by full lines in released position and by dotted lines in restraining position.

It will be noted that a door equipped with this latch is not to be provided with handles. To close the door from the outside it is merely necessary to thrust against it. This will cause the rounded surface 13 and head 11 to come against keeper 5 and the keeper will flick the head backwardly, thrusting through bolt 7 against spring

18. After the bolt head 11 has moved with the door to closed position, the spring 18 will promptly project the head 11 into the keeper as shown in Figure 5 thus fastening the door. The door cannot now be opened by pulling on it because the detent 19 prevents the head from swinging out of engagement with its keeper. It might be stated that when it is desired to close the door from the inside, one or more fingers of the user can be placed within the socket C at 10 the inner side of the door and the door thus pulled shut.

To open the door from the outside the user depresses the head or push bar 30 so as to push through rod 28 against lever 25 and cause one 15 end of the lever to lift against the action of spring 31 and thus raise the equalizing lever 23 to the position indicated by dotted lines in Figure 3. This results in lifting detent 19 away from the side of enlargement 15 and if the user 20 will then pull on the door, using the socket as a handle portion, the flat side 14 of head 11 will be deflected by the fixed keeper 5 so that the joint between head 11 and bolt 7 will "break", as shown in Figure 7, thereby allowing the head 25 11 to slip past the keeper. During this "breaking" action the bolt 7 will of course swing out of normal position against the action of springs 10 and 18 but as soon as the head 11 has passed its keeper 5, the springs will return the bolt and 30 its head to position flat against the adjacent side 2 of casing 1, the parts thus being restored to their normal positions.

To open the door from the inside the same action takes place with the exception that the user depresses the head or button 30 at the inner side of the door so that motion will be transmitted through the rod 28 thereof to the lever 26 which will be actuated to raise the equalizing lever 23 and the detent 19. The user then thrusts 40 against the door and causes it to open at which time the bolt and its head will act as before described.

Should the occupant of the car leave the stop 32 in holding position, as indicated by broken lines in Figure 3, it would then be impossible 45 for the door to be opened from the outside because equalizing lever 23 could not be raised by depressing the head or push bar 30.

While it is preferred to use a depressible head or push bar for actuating the lock it is to be understood that a lever could be used for this purpose if so desired. This modified construction has been shown in Figures 10 to 13 inclusive. It includes a lifting rod 34 extending upwardly 55 from detent 19 and pivotally attached to a cross head 35 the end of which normally rests on supporting lugs 36. A spring 37 is attached to the lifting rod and to the wall of the casing so as to hold said rod normally pulled downwardly so that the cross head 35 is normally resting on lugs 36 and detent 19 is normally positioned at the side of head extension 15.

Parallel shafts 38 take the place of the operating levers 25 and 26, these operating elements or shafts 38 being provided with lifting fingers 39 which extend toward each other and under a pin 40 carried by the rod 34. Thus when either finger 39 is swung upwardly it will push against the pin 40 and cause the rod 34 to move upwardly against the action of spring 37, thereby lifting the detent 70 away from the head of the bolt.

The respective operating elements or shafts 38 are adapted to be actuated by arms or levers 41 extending upwardly therefrom through slots in 75

the bottom wall of the window opening. By swinging either of these arms in one direction its shaft will be rotated so as to cause the finger 38 to thrust upwardly against pin 40 and release the bolt head for lateral swinging movement. This modified lock will be provided with a stop 32 corresponding with the one heretofore described whereby the latch can be held against operation.

What is claimed is:

- 10 1. A latching mechanism for a closure comprising a case plate provided with a face plate, a bolt carried thereby including a tail-piece and a head pivotally connected thereto, spring means for urging the bolt to latching position, said head being adapted to swing in response to opening movement of the closure and having sliding cooperation with said case plate and face plate during such swinging movement, a stop portion on said head engaging said face plate for limiting the 15 movement of the bolt to latching position and slidably engaging said face plate during swinging movement of the head, means for urging said bolt toward the face plate for rectilinear sliding movement to yieldably restrain swinging movement of the head, and movable abutment means 20 engaging said stop portion for maintaining the tail-piece and the bolt in alignment for rectilinear movement only whereby the closure is maintained in latched condition by preventing swinging 25 movement of the head.

2. A latching mechanism for a closure comprising a case plate provided with a face plate, a bolt carried thereby including a tail-piece and a head pivotally connected thereto, spring means for 35 urging the bolt to latching position, said head being adapted to swing in response to opening movement of the closure and having sliding cooperation with said case plate and face plate during such swinging movement, a stop portion on said head engaging said face plate for limiting the 40 movement of the bolt to latching position and slidably engaging said face plate during swinging movement of the head, means for urging said bolt toward the face plate for rectilinear sliding movement to yieldably restrain swinging movement of the head, and movable abutment means 45 engaging said stop portion for maintaining the tail-piece and the bolt in alignment for rectilinear movement only whereby the closure is maintained in latched condition by preventing swinging movement of the head.

50 in latched condition by preventing swinging movement of the head, and manual control means

for releasing said abutment means including means disposed on each side of the door and connections enabling actuation of one control independent of the other control.

3. A latching mechanism for a closure comprising a case plate provided with a face plate, a bolt carried thereby including a tail-piece and a head pivotally connected thereto and having sliding cooperation with said case plate and face plate during swinging movement, said head being 10 adapted to swing in response to opening movement of the closure, spring means for urging the bolt to latching position, means for urging said bolt toward the case plate for rectilinear sliding movement to yieldably restrain swinging movement of the head, and movable abutment means 15 for maintaining the tail-piece and bolt head in alignment for rectilinear movement only whereby the closure is maintained in latching condition by preventing swinging movement of the head 20

4. A latching mechanism for a closure comprising a case plate provided with a face plate a bolt carried thereby including a tail-piece and a head pivotally connected thereto, said head being adapted to swing in response to opening movement of the closure, a curved surface on said head adapted to slidably contact said case plate during swinging movement thereof, a stop portion on said head slidably engaging said face plate during swinging movement and in cooperation with said 30 curved surface, spring means for urging the bolt to latching position, means for urging said bolt toward the case plate for rectilinear sliding movement to yieldably restrain swinging movement of the head, and movable abutment means for maintaining the tail-piece and bolt head in alignment for rectilinear movement only whereby the closure is maintained in latched condition by preventing swinging movement of the head 35

5. A latching mechanism including a casing 40 having a face plate, a sliding and swinging bolt in said casing, means adapted to urge said bolt to a position for sliding movement, means carried by the bolt engaging the face plate to limit outward sliding movement thereof and coacting with the 45 face plate during swinging movement of the bolt, and releasable means engaging the last named means to restrain swinging movement of the bolt to unlatching position.

50 CLAUD H. SAXTON.
